ROBERT D. BEATTY, OF BIRMINGHAM, ALABAMA

DETONATOR

Application filed August 18, 1930. Serial No. 475,900.

My invention relates to a device for detonating high explosives and adapted particularly for use in detonating explosives in holes of relatively great depth, as in rock quarries and the like.

The particular object of my invention is to provide a device of the character designated which shall be effective to produce detonation of a deep charge in such a manner as to be as effective as a relatively shallow charge.

In the accompanying drawings forming a part of this application,

Fig. 1 is a sectional view through a quarry face illustrating the effect of detonation of high explosives as heretofore practiced and as carried out by means of my invention;

Fig. 2 is an enlarged cross sectional view showing my invention in place in a hole ready for firing; and

Fig. 3 is a cross sectional view showing my improved detonating tube.

In the use of high explosives in certain work, such as in rock quarries, it often happens that holes are sunk to a depth of more than 100 feet and filled for a major portion of their depth with dynamite, or similar high explosive, and tamped on top the high explosive. The rate of detonation of dynamite varies from 3000 to 11,000 feet per second. With a hole of such depth the lag in time between the explosion of the upper part of a charge of dynamite detonated at the top ahead of the lower portion is so great as to open fissures through the rock in the upper part and the force of the lower portion dissipates itself through these fissures.

This difficulty led to the practice of providing a small tube of explosive having a higher rate of detonation than dynamite and adapted to be detonated from the top. This tube was lowered into the hole before the dynamite was packed in. Its higher rate of detonation was depended upon to detonate the charge of dynamite in the lower portion of a deep hole before fissures had opened in the rock surrounding the upper portion to such an extent as to allow the lower portion of the charge to dissipate itself. As an example of such detonating explosive, there is

now sold to the trade, under the name of "Cordeau", a continuous metallic tube filled with T. N. T., or similar explosive, and which may be cut into appropriate lengths and lowered into a hole to be fired.

In firing deep holes, I have found that, despite the higher rate of detonation of the explosive in such a tube, there is still sufficient lag in time that a portion of the lower part of a deep charge is dissipated through fissures, and there is left a "toe" or undisturbed portion of the rock represented by the area illustrated in Fig. 1, lying between the dotted lines A and B at the base of the rock face 10 to be loosened.

In order to overcome the before mentioned difficulties I began the practice of detonating a tube of "Cordeau", with dynamite packed around it, from the bottom of the hole by placing a detonating cap on the bottom of the tube before lowering it into the hole, attaching wires thereto for connection to a suitable source of electrical energy and lowering the tube, cap and wires into the hole before packing with dynamite. Difficulties were at once experienced in maintaining the wires and cap in place during the lowering of the tube and packing of the hole, so that shots sometimes missed fire, making it necessary to detonate the charge from the top after surrounding holes had been fired, a dangerous and wasteful procedure.

In order to insure the detonation of charges such as have been described from the bottom, I designed and have since used the device illustrated in Figs. 2 and 3 of the drawings. This device consists of a tube 11 preferably made of lead or a compound thereof whereby it may be wound upon drums and readily straightened out for use for the purposes described. The tube 11 is filled with an explosive 12 having a high rate of detonation, such as T. N. T. Surrounding the tube 11 is a casing or winding 13 made of fabric or other equivalent material and between the casing 13 and the tube 11, are interposed a pair of insulated wires 14 and 16 which are bound under the casing during the process of manufacture so that the wires are always coextensive with the tube 11.

A detonating cap 17, having detonating wires 18 and 19 permanently secured thereto, is fitted over the end of the tube 11, the lower end of the tube 11 being bared sufficiently to accommodate the cap 17. The cap 17 is secured in place by means of a well known clamping device comprising a ring 21 crimped to the tube 11 at 22, as shown in the drawings, and having a plurality of fingers 23 extending downwardly around the cap 17 and being drawn thereagainst by means of a ring 24. The wires 18 and 19 are then tied at 26 to the wires 14 and 16 surrounding the tube. The tube 11 and wires 14 and 16 are then cut off at or near the top of the hole and the hole is suitably packed in its lower portion with dynamite shown at 27. The upper part is tamped as illustrated at 28 and the hole is ready for firing. By connection of the wires 14 and 16 to a suitable source of electric energy, not shown, the cap 17 is detonated followed by detonation of the high explosive 12 and of the dynamite 27.

I have found that when shots are detonated in the manner just described, the lower part of the face 10 shown in Fig. 1 is broken off along the line B thereby avoiding the "toe" left by the explosion of a charge from the top downwards.

From the foregoing it will be apparent that I have devised an improved detonating device which is simple of design, easy to manufacture, and which provides a means whereby a charge of high explosive in deep holes may be readily detonated from the bottom. The wires 13 and 14 being bound integrally with the tube 11 during the process of manufacture are handled as an integral part of the tube, being cut off with the tube where it is lowered into the hole, thereby being always available for connection to the detonating cap and to the source of electric energy, and also being coextensive in length with the tube 11.

While I have shown my invention in but one form, it will be obvious to those skilled in the art that it is not so limited, but is susceptible of various changes and modifications, without departing from the spirit thereof, and I desire, therefore, that only such limitations shall be placed thereupon as are imposed by the prior art or as are specifically set forth in the appended claims.

What I claim is:

1. In a detonating device a metallic tube packed with high explosive and adapted for insertion in a hole to be fired, said tube being adapted to receive a detonating cap on the end thereof, a fabric casing for the tube, and electrical conducting means disposed between the casing and the tube and adapted for connection to the detonating cap.

2. In a detonating device a metallic tube packed with high explosive and adapted for insertion in a hole to be fired, said tube being

adapted to receive a detonating cap on the end thereof, a fabric casing for the tube, and a pair of wires disposed between the casing and the tube and adapted for connection to the detonating cap.

3. As an article of manufacture, detonating tubing filled with high explosive, and carrying associated therewith and adapted to be cut off in lengths therewith, wires for attachment to a percussion cap.

4. As an article of manufacture, detonating tubing adapted to be filled with explosive and wound on reels and carrying associated therewith and adapted to be cut off in lengths therewith, wires for attachment to a percussion cap.

In testimony whereof I affix my signature.

ROBERT D. BEATTY.
